UNITED STATES PATENT OFFICE

166,004

MATCHBOOK CASE OR SIMILAR ARTICLE

David Sobel, Revere, Mass.

Application April 14, 1951, Serial No. 14,833

Term of patent 3½ years

(Cl. D48—29)

To all whom it may concern:

Be it known that I, David Sobel, a citizen of the United States, residing at Revere, in the county of Suffolk, in the Commonwealth of Massachusetts, have invented a new, original, and ornamental Design for a Matchbook Case or Similar Article, of which the following is a specification, reference being had to the accompanying drawing, forming a part thereof, in which:

Figure 6 is a front perspective view showing said matchbook case in open position; and

I claim:

The ornamental design for a matchbook case or similar article, substantially as shown.

DAVID SOBEL.
